UNITED STATES PATENT OFFICE.

ARTHUR KAISER, OF BROOKLYN, NEW YORK.

POCKET FOR SWEATERS.

Application filed March 20, 1924. Serial No. 700,476.

To all whom it may concern:

Be it known that I, ARTHUR KAISER, a citizen of the United States, residing in the borough of Brooklyn, in the county of Kings, city and State of New York, have invented certain new and useful Improvements in Pockets for Sweaters, of which the following is a specification.

My invention relates to a new and improved pocket for a sweater and a method of making the same.

One of the objects of my invention is to make a pocket for a sweater in which the pocket portion will be knit to the body portion of the sweater.

Another object of my invention is to provide a pocket which will have a reinforced top at the body of the sweater.

Another object of my invention is to provide a method for affixing the fabric for the pocket of a sweater, to the body of the sweater as part of the general knitting operation of forming the sweater.

Other objects of my invention will be set forth in the following description and drawings which illustrate a preferred embodiment thereof.

Fig. 1 is a rear view showing a portion of the sweater, part of the body portion being broken away to show the finished edge of the pocket.

Fig. 2 is a section on the line 2—2 of Fig. 1.

Fig. 3 is a top view illustrating the removal of some of the loops from one of the series of knitting needles.

Fig. 4 is a side elevation showing how the loops are removed from some of the needles of one series to the adjacent needles of the adjacent series.

Fig. 5 is a diagrammatic perspective view showing one stage of the knitting operation.

Fig. 6 is a diagrammatic perspective view showing the next stage in the knitting operation and illustrating the removal of some of the loops from some of the needles of one series to the adjacent needles of the adjacent series.

Fig. 7 is a top view illustrating the first stage in producing the finished and reinforced edge in the body of the sweater.

Figs. 8, 9 and 10 are diagrammatic top views illustrating the subsequent stages in the formation of the reinforcement at the edge of the pocket.

Fig. 11 is a diagrammatic perspective view showing the connection of the pocket portion to the knitting needles.

Fig. 12 is a front elevation showing how the sides and bottom of the pocket fabric are connected to the body by stitches.

Heretofore pockets have been formed in sweaters by knitting the sweater in the ordinary manner, and by then sewing to the sweater a separately knit and entirely independent piece of fabric, on the front of the body of the sweater.

The result was that the pocket often yielded or gave way, especially if heavy objects were carried in the pocket of the sweater, and the pocket bulged out at the front of the sweater, and produced an unsightly effect.

According to my new and improved method a new and improved pocket construction is secured in that the pocket fabric is directly knit to the body of the sweater, and the pocket fabric is located at the rear of the body portion of the sweater. The edge of the pocket in the front of the sweater is reinforced and finished.

Figs. 3 and 4 illustrate a conventional type of knitting machine having a front series of needles N and a similar rear series of needles N'. The needles N move between the ordinary guides G. The thread T is fed between the needles by any suitable mechanism so that each needle forms a rib of the knitted fabric. The ordinary parts of the well known type of knitting machine are not illustrated in detail because my invention is not dependent upon any special construction of knitting machine.

According to my invention, after the fabric of the body of the sweater has been knit to the point at which it is desired to form the pocket, then a suitable number of loops are transferred by a hand needle N' from some of the front series of needles N to the adjacent needles N of the rear series. This can be done very simply by opening the barbs B of the front needles and removing the loops to the adjacent rear needles as shown in Fig. 6.

The needles whose loops are thus transferred are the intermediate needles so that, for example, the loops of a central group of eleven needles can be thus transferred while the needles at both sides of the said central group retain their loops in the customary manner. The customary location of the loops

is shown in Fig. 5. After eleven loops have been thus transferred the said loops of the body 1 are then connected with the usual thread T, used as part of the knitting operation, by means of a hand needle N' having the barb B'. For this purpose the thread T is doubled so that the central part of the bight thus formed is engaged by the head of the needle N'. This bight is then pulled through 10 a pair of the loops L upon one of the rear needles N as illustrated in Fig. 7. The bight is then pulled to the right until it is directly behind the next pair of loops L and the needle N' is then pushed through the next pair 15 of loops L while the said bight remains at the rear of the second pair of loops L. The barb B' of the needle N' is now opened and the thread T is led around the shank of the needle N' behind the barb B' and then the 20 rest of doubled thread T is led through the eye of the needle N'. The needle N' is now pulled rearwardly. The barb B' is moved to the closed position when the needle N' is pulled through the second pair of loops L, 25 because the loops L have a sufficiently small diameter to produce this effect, which in itself is well known as part of the ordinary operation of the needles in a knitting machine. A second bight is thus formed in the 30 thread T which is forced through the first bight illustrated upon the shank of the needle in Fig. 9 and in Fig. 10 so that the first and second pair of loops are thus connected by the thread T. This operation, which begins 35 with the left hand pair of the eleven pairs of loops is continued until the central group of eleven loops have been thus connected, thereby producing a finished, connected and reinforced series of pairs of loops 40 at the point where it is desired to form the edge portion of the pocket.

The eleven pairs of loops forming the finished and reinforced edge of the pocket are now removed from the back group needles, 45 so that the fabric is now held by needles at both sides of this central group, and there are temporarily no loops on the eleven needles constituting this group. In Fig. 11 the series of connected eleven pairs of loops are 50 omitted, for the sake of clearness.

The pocket fabric P is now placed between the needles as illustrated in Fig. 11 and the loops thereof are separated so that half of said loops are placed upon the eleven front needles N of said group and the other half are placed upon the rear needles. Hence, 55 each of the rear central group of eleven needles each has one loop thereon and the corresponding front needles of the said central group again has one loop thereon. The knitting operation of the machine is then continued in the ordinary manner so as to produce a sweater having a body knit in the ordinary manner together with a pocket portion whose top is connected to the body 60 65

as part of the knitting operation. The piece of fabric for forming the pocket is separately knit before it is connected to the needles. However, the top of the fabric P is integral with the body 1 of the sweater, while 70 a reinforced top edge 2 is formed in the pocket.

The completed sweater may have the sides and base of the pocket connected to the body of the sweater by stitches S. 75

The completed sweater therefore has a pocket which is integral with the body of the sweater.

The completed sweater has a continuous front portion, save at the point where the finished and reinforced top or edge of the pocket has been formed, and a completely concealed rear pocket portion. The sweater so formed is of superior strength and appearance. It will be noted that the portion 80 of the body of the sweater directly above the pocket portion is knit integral with said pocket portion, so that the sweater and pocket portion constitute a single piece of knit fabric, said single piece having an integrally knit branch constituting the rear pocket portion. My invention is applicable 85 to all knit garments. 90

I have shown a preferred embodiment of 95 my invention, but it is clear that numerous changes and omissions could be made without departing from its spirit.

I claim:

1. A knitted sweater or the like comprising a knitted body member having a continuous series of intermediate loops thereof separated from the other loops thereof, said separated loops being connected to form a finished edge, and a rear knitted pocket member comprising a separate single thickness of flat knitted fabric having its upper edge directly knitted to the loops of said body member directly adjacent said separated loops to form a connection having the same thickness as the portions of said body member directly above and below said connection, the bottom and side edges of said pocket being connected to said front member. 100 105 110 115

2. In the art of knitting a sweater or the like having a body formed of a plurality of 120 series of connected loops, those steps which consist in connecting a plurality of one of the series of loops formed during the knitting of the body of the sweater to the adjacent loops of an adjacent series of said body so as to form a finished edge, and then connecting a flat and separately knitted pocket member which is formed of fabric having a plurality of series of connected loops to the body of said sweater directly adjacent said finished edge by separating the series of loops at the edge of the said pocket member and continuing the knitting operation with the loops of said pocket member to form the aligned portion of the body of the sweater, 125 130

while continuing the knitting with the loops of said body lateral to said finished edge.

3. In the art of knitting a sweater or the like having a body formed of a plurality of 5 series of connected loops, those steps which consist in knitting a portion of the body of the sweater, then connecting a plurality of one of the series of loops of said body formed in the knitting operation to the adjacent 10 loops of an adjacent series of said body, and

also securing each pair of connected loops to the other pairs of connected loops, and then continuing the knitting operation of the body above the connected loops in continuation of an additional piece of separately 15 knitted fabric, and at the sides of said additional piece.

In testimony whereof I hereunto affix my signature.

ARTHUR KAISER.
